UNITED STATES PATENT OFFICE.

EUGENE GARRETSON, OF BUFFALO, NEW YORK.

DESIGN FOR A CASING FOR THERAPEUTIC INSTRUMENTS.

45,804.

Specification for Design.

Patented May 19, 1914.

Application filed February 25, 1914. Serial No. 821,002. Term of patent 14 years.

To all whom it may concern:

Be it known that I, EUGENE GARRETSON, a citizen of the United States, residing at Buffalo, in the county of Erie and State of New York, have invented a new, original, and ornamental Design for a Casing for Therapeutic Instruments, of which the following is a specification, reference being had to the accompanying drawing, forming part thereof.

Figure 1 is a side elevation of a casing for

therapeutic instruments showing my new design. Fig. 2 is a front end view of the same. Fig. 3 is a rear end view of the same.

I claim:

The ornamental design for a casing for therapeutic instruments, as shown.

EUGENE GARRETSON.
